(57) **CLAIM**

The ornamental design for a diamond facet socket, as shown and described.

DESCRIPTION

FIG. 1 is a first perspective view of a diamond facet socket showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof.

FIG. 9 is an exploded front perspective view thereof; and, FIG. 10 is an exploded rear perspective view thereof.

In the drawings, the broken lines are for the purpose of illustrating portions of the diamond facet socket that form no part of the claimed design.
